UNITED STATES PATENT OFFICE.

FRANCES A. FOSTER, OF SIOUX CITY, IOWA.

KINDERGARTEN-LOOM.

SPECIFICATION forming part of Letters Patent No. 700,636, dated May 20, 1902.

Application filed February 5, 1902. Serial No. 92,739. (No model.)

To all whom it may concern:

Be it known that I, FRANCES A. FOSTER, a citizen of the United States, residing at Sioux City, in the county of Woodbury and State 5 of Iowa, have invented new and useful Improvements in Kindergarten-Looms, of which the following is a specification.

This invention relates to kindergarten-
10 looms, and although I do not wish to restrict
the invention to any particular use it is of de-
cided utility as an adjunct to manual primary
school teaching. Said loom is exceedingly
light, simple in construction, it is reversible
15 and requires only one hand to hold it, and it
is adapted either to right or left hand pupils.

The loom in the present case has end bars
20 provided with bores and the bores on one of
the bars extending entirely through the same,
and the bar which is provided with said last-
mentioned bores has a longitudinal groove or
25 channel, and a stop of suitable kind is held
in said groove and is engaged by the ends of
a plurality of rods projecting into the bores
in the bar carrying said stop, while the op-
posite ends of said rods fit into said other
30 bores, and the stop normally prevents the end
bars from moving toward each other, and the
end bars are provided with means for receiv-
ing a warp-thread.

35 The invention includes other objects and
advantages which with the foregoing will be
set forth in the following description, while
the novelty thereof will be covered by the
claims appended to said description, and the
40 said invention is clearly represented in the
accompanying drawings, forming a part of
this specification, and in which—

Figure 1 is a plan view of a hand-loom in-
cluding my improvements, together with the
45 needle or shuttle. Fig. 2 is a view from one
edge of said loom with the stop slightly with-
drawn. Fig. 3 is a longitudinal sectional ele-
vation, the section being in the line 33, Fig. 1.

Like characters refer to like parts in all the
45 figures.

I desire to state that the invention is not
limited to the exact construction disclosed by
said drawings and description, nor to the mak-
ing of the different parts of any particular
50 material, for many variations as to these points
may be made within the scope of my claims.

The loom includes in its construction end

bars 5 and 6, which may be conveniently made
from wood. Said end bars 5 and 6 are bored
transversely thereof, the bores in the bar 5 55
being denoted by 7, while the other bores are
designated by 8. It will be seen that the bores
7 extend entirely through their end bar, while
the bores 8 extend partially through their
bar. There are four bores in each end bar, 60
although, of course, this number may be var-
ied, and the bores in the respective bars form
seats for rods 9 and 10, which may consist of
wire. By making a greater number of bores
65 than rods in the respective bars said rods can
be moved toward or from each other to vary
the effective width of the loom.

To assemble the device, one end of each rod
will be inserted in a bore 8 until said end is
bottomed, after which the opposite ends of 70
said rods will be thrust into corresponding
bores 7, the end bars and rods when thus as-
sembled presenting substantially a rectan-
gular structure the relation of which is main-
tained by a stop 11, which fits into a groove 75
or channel 12, extending the entire length of
the end bar 5 and which abuts against or is
contiguous to the ends of the rods 9 and 10
in their bores 7. The stop 11, which may be
made from wire, is held in place and guided 80
in its movements by staples 12^a, any suitable
number of which may be employed and the
branches of which straddle the stop and are
driven into the end bar 5. For cheapness
and simplicity the staples are provided to 85
hold and guide the stop, though of course
equivalent means may be employed for this
purpose.

With the parts assembled as shown in Fig.
1 and if it be desired to knock down the 90
loom the stop 11 will be withdrawn from its
groove, and when it has passed across the
outermost one of the series of bores 7 the end
bar 5 will be slipped off the ends of the rods
9 and 10, after which the end bar 6 will be 95
drawn off the opposite ends of said rods, at
which point the rods can be pulled from the
work.

To facilitate the operation of the stop 11, it
is provided at one end with a finger-piece 13, 100
formed by a bend or crank portion, and to
secure ready assemblage of the parts the ends
of the rods when they enter the bores 7 are
reduced or tapered.

The warp is denoted by 14 and like the weft may be of any suitable material, and it is shown as formed of a continuous thread and is held in place by rows of relatively closely arranged studs or tacks 15 driven into the bottoms of grooves 16, formed on the inner upper sides of the end bars.

It will be seen that the bores 7 and 8 are arranged very close to the tacks, so that when 10 the warp is strung strands of said warp can be run along the rods 9 and 10, the ends of which are fitted into said bores.

The warp-thread will be put on as follows: Fasten one end of said thread to an outside 15 tack at either end of the loom, then pass it along the adjacent side rod, then pass it around two tacks at the corresponding end of the loom, and then continue until the loom is filled. The outermost threads of course 20 are not used in weaving, they being intended to take the place of the rods when the work is taken from the loom. When the loom is strung, the free end of the warp-thread can be suitably fastened—for example, by being 25 secured to a tack 17.

The needle or shuttle is denoted by 18, and it is made of some light material, such as tin, and the weft can be wound on the said needle, as indicated. The free end of the weft- 30 thread will then be fastened to one end of a side rod, after which the needle will be passed over and under the successive warp-threads, as is customary, the loom being turned over after each course and the needle being employed to press down the work into compact 35 form. In refilling the needle it is not necessary to knot the ends of the weft-thread, but such ends should be overlapped and preferably near the center and away from the sides 40 of the work. These loose ends may be clipped without danger of unraveling.

After the work is finished the loom can be separated, as hereinbefore described, and the side wires can be taken from the work.

45 The rods 9 and 10 serve to maintain a uniform width of the work. The stop 11 performs an important function, as will be now set forth. Heretofore some difficulty has been experienced in removing the 50 work from hand-loom, owing to the fact that the end bars could not be moved toward each other. By virtue, however, of the said stop the removal of the work from the frame is much facilitated, for by slipping said stop 55 from across the pointed ends of the rods 9 and 10 the bar 5 can be readily moved toward the

companion bar 6 a distance sufficient to cause the loosening of the warp, so that the ends of the same can be quickly freed from the studs or tacks 15.

Having described the invention, what I claim is—

1. A loom having end bars provided with bores and the bores on one of the bars extending entirely through the same and the 65 bar that has the bores extending entirely through the same also having a longitudinal groove, rods the ends of which are fitted in said bores, and a stop for said rods fitted in said groove.

2. A loom having end bars provided with bores and one of the bars extending entirely through the same and the bar that has the bores extending entirely through the same also having a longitudinal groove, the ends 75 of which are fitted in said bores, a stop for said rods slidable in said groove, and guiding means for said stop.

3. A loom having end bars provided with bores and the bores on one of the bars extending entirely through the same and the bar that has the bores extending entirely through the same also having a longitudinal groove, the ends of which are fitted in said 80 bores, a stop for said rods slidable in said groove and staples straddling said stop.

4. A loom having end bars provided with bores and rods fitted in the bores, the bores being of greater number in the respective bars than the rods and extending transversely 90 of the bars and the bores of one of the bars extending entirely through the same, and said bar that has the bores extending entirely across the same having a longitudinal groove, and a stop for said rods in said groove.

5. A loom having end bars provided with bores and the bores on one of the bars extending entirely through the same and the bar that has the bores extending entirely through the same also having a longitudinal groove, 100 the ends of which are fitted in said bores, a stop for said rods fitted in said groove, and headed studs carried by the end bars, for receiving the warp.

In testimony whereof I have hereunto set 105 my hand in presence of two subscribing witnesses.
